UNITED STATES PATENT OFFICE.

ALPHONSO T. PALMER, OF CHICAGO, ILLINOIS.

SWITCH-POINT GUARD.

Application filed February 15, 1926. Serial No. 88,183.

This invention relates to a device for protecting the point of a railroad switch against wear by the wheels of trains passing over the switch. The object of the invention is to provide a switch point guard which shall be of improved construction, economical to manufacture and efficient in operation, and in which the wearing member may be easily removed and replaced, as required.

The invention is exemplified in the combination and arrangement of parts shown in the accompanying drawings and described in the following specification, and it is more particularly pointed out in the appended claims.

In the drawings—

Figure 1 is a side elevation of a railroad rail having a guard applied thereto, embodying one form of the present invention;

Figure 2 is a section on line 2—2 of Figure 1;

Figure 3 is a top plan view of the railway rail and the end of a switch point showing the relation of the guard to the switch point.

In the drawings, the numeral 10 designates a railway rail having a guard secured thereto. The guard comprises a stand 11 and a guard blade 12. The stand 11 includes a plate 13 and reinforcing ribs 14 arranged in spaced relation thereon. At the top of the plate 13 and extending longitudinally thereof, there is provided an enlargement or head 15 having a longitudinal notch 16 for holding the blade 12. The notch 16 is narrower at the top than at the bottom so that the blade 12 is dovetailed into the notch. The blade is driven into the notch from one end thereof and may be made to fit tightly so that it will be retained in place by friction between the sides of the plate and the inner surface of the notch. If desired, the head 15 and plate 13 may be provided with registering opening 17 in which pins 18 may be driven to prevent longitudinal movement of the blade within the notch. The lower edge of the plate 11 and the ribs 14 are beveled to conform to the inclination of the upper surface of the rail flange. In like manner, the inner lip 19 of the head 15 is beveled to fit the under surface of the head of the rail. Spaced lugs 20 extend inwardly from the lip 19 and have their upper edges flush with the beveled upper face of the lip 19. The stand 11 forms a strut which bridges the space between the lower flange and the head of the rail and is wedged into place between the inclined faces

of these rail parts and is held in position by bolts 21 which pass through openings 22 in the plate 13 and through openings 23 in the rail web. A spring plate 24 is fitted over the projecting ends of the bolts 21 and is clamped down by a nut 25. The spring plate 24 may be similar to that shown in my prior Patent No. 1,281,823, granted September 16, 1918. This plate, when the nuts 25 are tightened down, exerts continual spring pressure on the bolts holding the stand 11 firmly wedged into place between the upper and lower rail parts. The guard is secured to the rail with the end of the blade 12 closely adjacent the end of the switch point to be protected, this point being shown at 26 in the drawings.

When a railway train is approaching the switch point 26 from the right, as shown in Figure 1, the wheel flange will strike the blade 12 prior to engagement with the end of the switch point so that the wheel flange is directed onto the switch point without striking the end of the point. In this way, the switch point is protected against wear and the life of the switch is greatly increased. The blade 12 is preferably made of manganese steel as this material efficiently resists wear. After the blade has become worn, it may be easily removed by driving the pins 18 out of the holes 17 and then driving the blade 12 endwise from its socket 16. A new blade may then be driven into place and the device is as good as new. The stand 13 need not be removed from its connection with the rail for replacing the blade 12. The stands will last indefinitely as they are not subjected to wear. After the rail has become worn, sufficiently to require its removal, the stand 13 may be removed from the rail and applied to the new rail substituted. The stand will, in fact, outwear many rails and the replacement of the blades is simple and inexpensive since each blade requires only a comparatively small amount of material. The saving is very considerable over the expense if the stand and blade were made of the same piece of manganese steel.

In Figure 2 of the drawings, the inner face of the blade is shown as lying flat against the face of the rail. The blade is constructed with the upper edge bent inwardly toward the rail an amount slightly greater than shown in Figure 2. This will cause the top edge of the blade to engage the rail face, but when the nut 25 is tightened, the blade will be sprung

sufficiently to bring the entire inner face against the face of the rail. This arrangement will insure close contact between the upper edge of the blade and the face of the rail at all times.

5 I claim:—

1. A switch point guard comprising a supporting stand, and a removable wear member carried by said stand and held thereby adjacent the lateral face of the railway rail.

10 2. A switch point guard comprising a stand arranged to be secured to a railway rail, said stand having a recess therein, and a blade of wear resisting material removably secured in said recess in position to engage the lateral face of the head of a rail.

15 3. The combination with a railway rail, of a switch point guard including a supporting stand comprising a strut member extending from the flange to the head of the rail, and a blade of wear resisting material removably supported by said strut member against the lateral face of the rail head.

20 4. The combination with a railway rail, of a switch point guard secured to said rail, said guard comprising a web member having tapered upper and lower edges arranged to engage the inner faces of the flange and head of said rail respectively, means for securing said web member to said rail, and a removable blade of wear resisting material carried by said web member adjacent the rail head.

25 5. The combination with a railway rail, of a web member secured to said rail and bridging the space between adjacent faces of the flange and head of said rail, said web member having a dovetailed notch in the upper edge thereof, and a web-shaped blade of wear resisting material removably held in said notch.

30 6. The combination with a railway rail, of a switch point protector secured to said rail, said protector comprising a plate having beveled upper and lower edges arranged to fit between the flange and head of said rail, bolts for securing said plate to said rail, said plate having vertical reinforcing ribs thereon, and a guard member of wear resisting material projecting upwardly from the upper edge of said plate and removably secured thereto.

35 7. The combination with a railway rail, of a switch point guard secured thereto, said guard comprising a stand extending from the upper face of the rail flange to the lower face of the rail head, and a removable wear member supported by the stand and projecting upwardly from the top thereof adjacent the side of said rail member.

40 8. The combination with a railway rail,

of a switch point guard secured thereto, said guard comprising a web having upper and lower beveled edges engaging the lower face of the rail head and the upper face of the rail flange respectively, vertical reinforcing ribs 65 on said web, and a blade of wear resisting material projecting upwardly from the upper edge of said web and bearing against the side of said rail member.

9. The combination with a railway rail, 70 of a switch point guard secured to said rail, said guard comprising a supporting stand having a blade extending upwardly therefrom adjacent the side face of the rail head, and bolts for holding said stand against said rail, said blade having the top edge inclined towards said rail so that said top edge will be resiliently held against said rail by the force exerted on said stand by said bolts.

10. The combination with a railway rail, 80 of a switch point protector therefor comprising a supporting stand, a wear member removably carried by said stand against the head of the rail, bolts for securing said stand to said rail, and a spring plate for exerting 85 yielding tension on said bolts.

11. The combination with a railway rail, 90 of a switch point protector comprising a plate disposed against one side of said rail and bridging the sides between the flange and head of said rail, spaced bolts extending through said plate and the web of said rail, a wear member removably supported by said plate adjacent the head of said rail, nuts for holding said bolts in position on said rail, 95 and a spring plate interposed between said nuts and rail, said plate being curved to exert resilient tension on said bolts.

12. The combination with a railway rail, 100 of a switch point protector therefor comprising a plate disposed against the side of said rail and having the upper and lower edges thereof beveled to fit the inclined faces of the head and flange of said rail respectively, said plate having lugs extending inwardly in contact with the lower face of said rail head, and having upright reinforcing ribs on the outer face thereof, the upper edge of said plate having a longitudinally extending dovetailed slot 105 therein, a wedge-shaped tongue of wear resisting material disposed in said slot and fitting against the lateral face of the rail head, and bolts extending through said plate and the web of said rail for holding said plate in position on said rail.

110

115 In testimony whereof I have signed my name to this specification on this 13th day of February, A. D. 1926.

ALPHONSO T. PALMER.
